UNITED STATES PATENT OFFICE.

PERLEY R. GLASS, OF BROOKLINE, MASSACHUSETTS, ASSIGNOR TO P. R. GLASS COMPANY, OF BOSTON, MASSACHUSETTS, A CORPORATION OF MASSACHUSETTS.

PUNCHING AND FOLDING MACHINE.

1,315,223.

Specification of Letters Patent. Patented Sept. 9, 1919.

Application filed April 1, 1916. Serial No. 88,291.

To all whom it may concern:

Be it known that I, PERLEY R. GLASS, a citizen of the United States, residing at Brookline, in the county of Norfolk and 5 State of Massachusetts, have invented certain Improvements in Punching and Folding Machines, of which the following description, in connection with the accompanying drawings, is a specification, like reference characters on the drawings indicating like parts in the several figures.

This invention relates to machines for operating upon the margin of a piece of flexible material and is herein illustrated in connection with a machine for folding the margin of a piece of upper leather and for forming along said margin a row of ornamental perforations.

It is customary to fold the margins of certain parts of shoe uppers and to ornament them by a row of fancy punch holes, and although vamps, foxings, etc., are very commonly so treated the present invention will, for convenience, be described in connection 25 with a machine specially adapted to fold and ornament shoe tips. The tip is ordinarily attached to the end of a short vamp by a row or rows of stitches located near one edge of the tip; and this edge, in a flat died-out 30 tip is slightly curved.

Hitherto it has been customary to skive the margin of the tip, then to cement the skived margin, then to fold said margin on a suitable machine and finally to form the 35 ornamental perforations by means of a punching machine. According to the present invention the skiving and cementing are carried out as before, but the folding and punching are accomplished progressively in 40 a single operation.

One feature of the invention comprises, in a machine of the class described, a support for a piece of stock, means for feeding said stock intermittently over said support, 45 means for forming a fold in the margin of said stock, means for hammering the fold, and means for punching the stock near the edge thereof after the fold has been made. With such a construction the two operations 50 of folding and punching are going on at the same time whereby the former practice of performing two separate operations is obviated and a large saving of time is effected.

Another feature of the invention comprises in a machine of this general type, a feed member movable in a path the curve of which corresponds approximately to the curvature of the edge of the material which is to be operated upon, and an edge gage to facilitate proper location of the stock with respect to the feed member. By these means is insured uniform folding and punching of the different pieces of material, a result which is difficult to secure when the two operations are performed separately.

These and other features of the invention including certain details of construction and combinations of parts will be described in connection with an illustrative machine by which an exemplary method may be carried out and will be pointed out in the appended claims.

Referring now to the accompanying drawings,—

Figure 1 is a front elevation of an illustrative machine in which the invention is embodied;

Fig. 2 is a perspective of the mechanism for moving the feed member and for operating the clamp;

Fig. 3 is a detail, partly in section, showing the connection between the clamp and the feed member;

Fig. 4 is a detail perspective of a portion of the clamp;

Fig. 5 is a perspective of the top of the machine;

Fig. 6 is a detail perspective of the punch and its operating mechanism;

Fig. 7 is a detail, principally in section, showing more particularly the whole punching mechanism, and

Fig. 8 is a perspective of a shoe tip which has been folded and punched on the machine.

The present invention is illustrated in connection with a folding machine which is similar to that shown and described in British Patent No. 15,405 of 1912. The present machine, like that of the patent, comprises a flat bed or support, herein shown as composed of two plates 1 and 3, over which the work is fed, a preliminary turning member 201, a pivoted gage 203, a creaser 205, a reciprocating folding finger (not shown) which rises from beneath the work and bends

the margin thereof about the end of the creaser to form the fold, and an oscillating hammer or presser 207 to press the fold thus formed. In the machine of the patent the 5 hammer coöperates with an anvil to grip the fold; and while the work is thus gripped the hammer and anvil are moved in a direction to feed the work. In the present machine the movable anvil and its operating 10 mechanism, as well as the mechanism for moving the hammer in the direction of feed, have been omitted, and a separate feed mechanism which will presently be described has been provided. No further description 15 of the folding and pressing mechanism will be given since its details of construction form no part of the present invention and any suitable folding and pressing mechanism may be employed. The particular mech- 20 anism illustrated in the present machine forms the subject-matter of certain prior United States Patents Nos. 1,270,753 and 1,281,555.

The two plates 1 and 3 have formed be- 25 tween them a segmental guideway 5 to receive a segmental rack 7 the curvature of which is approximately the same as the curvature of the edge of the piece of upper material which is to be operated upon. In 30 the operation of the machine the shoe tip 100 is clamped to the rack, and the rack is then moved to present the margin of the tip pro- gressively, first to the folding mechanism which has been indicated above, and then to 35 the punching mechanism shown in Fig. 7. The clamp 9 (see Fig. 3) is connected by a stem 11 with a block 13 having in it two vertical bores. A pin 15 driven tightly into a socket in the rack 7 is encircled by a spring 40 17 which tends always to hold the clamp 9 in contact with the rack 7. In order to maintain the clamp in proper alinement with the rack a second pin 19, loose in the second bore in the block 13, is held in a socket in the 45 under side of the rack 7 by a coiled spring 21, a handle 23 being provided to permit this pin to be withdrawn from engagement with the clamp when desired.

In order to raise the clamp 9 at the end 50 of the punching and folding operation, the lower end of the pin 15 has formed upon it a rack 25 with which a pinion coöperates, so that by turning the pinion the clamp 9 may be raised against the action of the 55 spring 17. Automatic turning of the pinion to raise the rack is accomplished through a crank 29 fast to the stem 127 of the pinion and a curved rod 31 having adjustably fastened thereon a stop collar 33 (see Fig. 1). 60 The rod is slidable through a hole in a part of the frame of the machine and moves with the segmental rack 7 until the collar strikes the frame, after which further forward movement of the rack causes the rod 31 to 65 pull the crank 29 and thereby to raise the

clamp 9. The clamp is held in raised position by a latch 35 pivoted to the block 13 and having an operative end which engages the upper portion of the rack 7 as shown in Fig. 2, a leaf spring 37 tending at all times to 70 move the latch toward and hold it in engagement with the rack.

The movement of the rack 7 is accom- 75 plished through gears 39, 41, beveled gears 43, 45, a clutch member 47 fast to the hub of the gear 45, a clutch member 49 slidable on the spindle 51 on which the beveled gear 45 is loosely mounted, and an intermittent grip device 53 rotatable on the spindle 51 and adapted to impart rotation to the clutch 80 member 49. Since any suitable intermittent grip device may be employed the one illus- trated will not be further described. On the back of the beveled gear 45 (see Fig. 1) is a tapered cam 55 which, when the beveled gear 85 has nearly accomplished a revolution, eng- ages an abutment on a yoke 57 between the arms of which the clutch member 49 is rev- olubly mounted, thereby swinging said yoke to the left about its pivot 59 and separating 90 the clutch members 47, 49. A spring pin 61 holds the yoke lightly as shown in its rear- ward position after the yoke has been moved as described above. When the yoke has thus been moved, the feeding rack 7 has reached 95 its extreme forward position, the clamp 9 has been raised by the pull of the rod 31, and the punched and folded tip may be removed from the machine. To permit the rack 7 to be returned to its initial position a strap 63 100 has one end fastened to a drum 65 which is integral with the hub of the beveled gear 45. When the rack has been returned to its initial position by pulling upon the strap 63 the clamp 9 is still raised to permit a 105 new tip to be placed in position, and the clutch members 47, 49 are still separated.

In order to cause these clutch members to engage so as to start the feeding movement of the rack and to trip the latch 35 so as to 110 permit the spring 17 to lower the clamp 9 upon the tip, the following mechanism, shown best in Fig. 2, is provided: A bell crank lever 67, the horizontal arm of which is connected with a treadle rod 69, has its 115 upright arm arranged to engage a boss on the yoke 57 when the treadle is depressed whereby the clutch member 49 is moved into engagement with the clutch member 47. This bell crank lever 67 is also connected 120 with a rod 71 slidable in a boss on the frame of the machine and provided at its upper end with an arm 73 which overhangs the tail of the latch 35, a spring 75 tending to hold the rod 73 and bell crank lever 67 in the 125 position shown. When, therefore, the treadle is depressed to throw in the clutch the arm 73 disengages the latch 35 from the rack 7 and permits the clamp 9 to be brought down upon the tip or other piece of work, the 130

parts being so constructed that the work is clamped just before the clutch is thrown in.

The intermittent grip device 53 is operated continuously through a link 77 pivoted at one end to a movable part of said device and at the other to an arm 79 fast on a rock shaft 81, said rock shaft having at its other end an arm 83 to the outer end of which is pivoted the upper end of a forked link 85 the lower end of which is pivoted to a block 87 adjustable in a slot in an arm 89 so that the extent of the intermittent feed movements may be regulated. The arm 89 is identical with the feed operating arm in the machine of the British patent referred to above. It is pivoted about a rod 91 and is oscillated continuously by an eccentric 93 on the driving shaft 95. If it is desired at any time to change the extent of the intermittent feed movements the position of the block 87 in the slot in the lever 89 may be changed by rocking about its pivot 133 a yoke 135 which embraces a pin 137 carried by said block. To facilitate so rocking the yoke, a rod 139 fast to the hub of said yoke projects through a slot in the front of the frame of the machine as shown in Fig. 1.

The punching is done from beneath, since the tip lies grain side down on the feed rack 7. The punch 97 (see Figs. 6 and 7) is mounted on an arm 99 pivoted to the frame of the machine at 101. The outer end of the arm carries a roller 103 held down on a cam 105 by a spring 107. The cam is fast to a gear 109 driven by a small gear 111 which is fast on the main driving shaft 95. The gearing by which the punch is actuated and the cams and levers by which the intermittent grip device 53 is actuated are proportioned and adjusted in accordance with the pattern of punch which is used. In the present machine, with the parts adjusted as shown, two intermittent feeds occur to one punching operation.

Referring now more particularly to Fig. 7, the punch block 113 has a stem 115 adjustably held by a set screw 117 (Figs. 1 and 5), an adjusting screw 119 being provided to facilitate proper positioning of the block. The block, as well as certain elements of the folding mechanism, is mounted upon an overhanging arm 112. The block is provided with a passageway having guides 121. Through the passageway, around the guides, and across the face of the punch block runs a strip of paper 123 which furnishes a backing for the tip during the punching operation and thereby insures clean cut punch holes. A U-shaped guide 125 adjustably fastened to the arm 112 holds up the upper run of the paper strip; and the strip is wound from one roll to another in any suitable manner, for example by a reel stand such as that shown in United States Pat-

ent No. 941,704, connected by a belt with a pulley 129 on the driving shaft 95. The operation of the machine is as follows:— Starting with the parts in the position shown in Figs. 1 and 2 with the clamp 9 raised and the rack 7 in its starting position which results from pulling down upon the strap 63, the operator places a tip 100 between the clamp and the rack with its edge which is to be folded against the gages 75 131. He then depresses the treadle rod 69, the effect of which is to trip the latch 35 thereby permitting the spring 17 to bring the clamp 9 down upon the tip and throwing the clutch members 47, 49 into engagement. The tip is then fed intermittently first past the folding and pressing mechanism and then past the punching mechanism with the result illustrated in Fig. 8. Toward the end of one revolution of the beveled gear 45, the cam 55 engages the yoke 57 to separate the clutch members, and the rod 31 exerts a pull on the crank 29 to raise the clamp 9, whereupon the latch 35 engages the rack as shown in Fig. 2 to maintain the clamp in raised position, and the feeding mechanism comes to rest in the position shown in said figure except that the rack is at the extreme end of its feeding movement. The operator then removes the punched and folded tip and pulls down on the strap 63 to return the rack to its initial position.

Although the invention has been set forth in connection with a particular machine, it should be understood that the invention is not limited in the scope of its application to the particular machine shown and described.

Having thus described my invention, I claim as new and desire to secure by Letters Patent:

1. A machine of the class described, having, in combination, a support for a piece of stock, means for feeding said stock intermittently over said support, means for forming a fold in the margin of said stock, means for hammering the fold, and means for punching the stock near the folded edge after the fold has been made.

2. A machine of the class described, having, in combination, a support for a piece of stock, means for feeding said stock intermittently over said support, means for forming a fold in the margin of said stock, means in the rear of said fold-forming means for hammering the fold, and means in the rear of said fold-hammering means for punching said stock near the edge thereof.

3. A machine of the class described, having, in combination, a support for a piece of stock, means for feeding said stock intermittently over said support, means for forming a fold in the margin of said stock, means in the rear of said fold-forming means for hammering the fold, and means in the rear of said fold-hammering means for punch-

ing said stock near the edge thereof, said hammering and punching means being timed to cause more than one hammering operation to each punching operation.

- 5 4. A machine of the class described, having, in combination, a support for a piece of stock, means for folding the margin of the stock, means for feeding the stock past the folding means, and automatic means for stopping the feed at the end of the folding operation.

10 5. A machine of the class described, having, in combination, a support for a piece of stock, means for folding the margin of the stock, means for clamping the stock and feeding it past the folding means, and automatic means for stopping the feed at the end of the folding operation.

15 6. A machine of the class described, having, in combination, a support for a piece of stock, means for folding the margin of the stock, means for clamping the stock and feeding it past the folding means, and automatic means for arresting the feed movement at a predetermined point.

20 7. A machine of the class described, having, in combination, a support for a piece of stock, means for folding the margin of the stock, means for clamping the stock and feeding it past the folding means, and automatic means for releasing the stock at a selected point in the feed movement.

25 8. A machine of the class described, having, in combination, a support for a piece of stock, means for folding the margin of the stock, means for clamping the stock and feeding it past the folding means, automatic means for releasing the stock at a selected point in the feed movement, and means permitting variation of said point.

30 9. A machine of the class described, having, in combination, a support for a piece of stock, folding and punching mechanisms for operating upon the stock, means for clamping the stock and moving the clamp past said mechanisms, and means for stopping the movement of the clamp at the end of the folding and punching operations.

35 10. A machine of the class described, having, in combination, a support for a piece of stock, folding and punching mechanisms for operating upon the stock, means for clamping the stock and feeding it past said mechanisms, and automatic means for stopping the feed at the end of the folding and punching operations.

40 11. A machine of the class described, having, in combination, a support for a piece of stock, folding and punching mechanisms for operating upon the stock, means for clamping the stock and feeding it past said mechanisms, and means for stopping the feed and releasing the stock at the end of the folding and punching operations.

45 12. A machine of the class described, hav-

ing, in combination, a support for a piece of stock, folding and punching mechanisms for operating upon the stock, means for clamping the stock and feeding it past said mechanisms, and automatic means for stopping the feed and releasing the stock at the end of the folding and punching operations. 70

13. A machine of the class described, having, in combination, a support for a piece of stock, folding and punching mechanisms for operating upon the stock, means for clamping the stock and feeding it past said mechanisms, an edge gage for facilitating presentation of the stock to said means, and means for stopping the feed and for opening the clamp at the end of the folding and punching operations. 75 80

14. A machine of the class described, having, in combination, a support for a piece of stock, folding and punching mechanisms for operating upon the stock, means for clamping the stock and feeding it past said mechanisms, an edge gage for facilitating presentation of the stock to said means, and automatic means for stopping the feed and for opening the clamp at the end of the folding and punching operations. 85 90

15. A machine of the class described, having, in combination, a support for a piece of stock, folding and punching mechanisms for operating upon the stock, and means for compelling said stock to move past said mechanisms in a path the curve of which corresponds approximately to the curve of the edge of the piece which is to be operated upon. 95 100

16. A machine of the class described, having, in combination, a support for a piece of stock, folding and punching mechanisms for operating upon the stock, and means 105 for moving said stock past said mechanisms in a path the curve of which corresponds approximately to the curve of the edge of the piece which is to be operated upon, said folding and punching mechanisms being 110 timed to cause more than one folding operation to each punching operation.

17. A machine of the class described, having, in combination, a support for a piece of stock, folding and punching mechanisms 115 for operating upon the stock, means for clamping the stock and feeding it past said mechanisms in a path the curve of which corresponds approximately to the curve of the edge of the piece which is to be operated 120 upon, and means for stopping the feed and releasing the clamp at the end of the folding and punching operations.

18. A machine of the class described, having, in combination, a support for a piece 125 of stock, folding and punching mechanisms for operating upon the stock, means for clamping the stock and feeding it past said mechanisms in a path the curve of which corresponds approximately to the curve of 130

the edge of the piece which is to be operated upon, and automatic means for stopping the feed and releasing the clamp at the end of the folding and punching operations.

5 19. A machine of the class described, having, in combination, a support for a piece of stock, edge folding mechanism, a segmental member movable with respect to said folding mechanism in a guideway on said support, said segmental member having a radius of curvature corresponding to that of the edge of the stock to be folded, a clamping element for holding a piece of stock on said member, and means for operating said member and folding mechanism.

10 20. A machine of the class described, having, in combination, a support for a piece of stock, edge folding mechanism, a segmental member movable with respect to said folding mechanism in a guideway on said support, a clamping element for holding a piece of stock on said member, means for operating said folding mechanism and clamp, a clutch for operating said segmental member, and automatic means for throwing out said clutch.

15 21. A machine of the class described, having, in combination, a support for a piece of stock, folding means including a creaser 30 and a coöperating folder which bends the margin of the stock over the creaser, means for pressing the fold, means for punching the fold, and means for feeding said stock intermittently past said folding, pressing 35 and punching means.

22. A machine of the class described, having, in combination, a support for a piece

of stock, folding and pressing mechanisms for operating upon said stock, and means for compelling said stock to move past said 40 mechanisms in a path the curve of which corresponds to the curve of the edge of the piece which is to be operated upon.

23. A machine of the class described, having, in combination, a support for a piece 45 of stock, folding and punching mechanisms for operating upon the stock, means for feeding the stock past said mechanisms, and automatic means for stopping the feed movement when the rear end of the stock 50 has passed said mechanisms.

24. A machine of the class described, having, in combination, a support for a piece of stock, means for feeding the stock intermittently over the support, mechanism for 55 forming a fold in the margin of the stock, mechanism for hammering the fold, and mechanism for forming a row of ornamental punch holes near the folded edge thereof, said folding, hammering and punching 60 mechanisms being located to operate upon the stock successively in the order named.

25. A machine of the class described, having, in combination, means for feeding the stock intermittently, means for 65 forming a fold in the margin of the stock, a hammer held for movement in the line of feed, means for causing the hammer to rise and fall so as to hammer the fold, and means for punching holes through both 70 plies of the folded margin.

In testimony whereof I have signed my name to this specification.

PERLEY R. GLASS.
